ROSS H. FORNEY, OF DALLAS, TEXAS, ASSIGNOR TO FORNEY COMBUSTION ENGINEERING COMPANY, OF DALLAS, TEXAS, A CORPORATION OF TEXAS

FUEL BURNER

Application filed April 9, 1932. Serial No. 604,165.

This invention relates to new and useful improvements in fuel burners.

One object of the invention is to provide an improved burner particularly adapted for atomizing fuel, and which may be constructed in an economical manner.

A particular object of the invention is to provide a burner including a removable plug or core arranged to co-act with the burner head to form the fuel passages, whereby such passages are provided on the surface of the plug. The advantage of such an arrangement is that ducts and ports which are ordinarily drilled or bored through the plug, and which are likely to become stopped up, are obviated. By providing the passages on the outer surface of the plug, such passages are fully exposed for cleaning and inspection when the plug is removed.

Another object of the invention is to provide a compact and simple structure arranged so that when the tip is removed the plug is carried thereby and the open end of the adapter, or the supply tube, is exposed, and thus made free to access.

A further object of the invention is to provide a burner of the atomizing type in which an ample storage chamber is provided contiguous to the tangential ducts, whereby an adequate supply of fuel is provided for said ducts.

Still another object of the invention is to provide a plug for a burner in which the fuel passages are formed in the outer surface so as to either be cast or readily cut therein, thus making for quicker and cheaper production.

A construction designed to carry out the invention will be hereinafter described together with other features of the invention.

The invention will be more readily understood from a reading of the following specification and by reference to the accompanying drawing in which an example of the invention is shown, and wherein:

Figure 1 is a longitudinal sectional view

of a burner constructed in accordance with the invention,

Figure 2 is an enlarged longitudinal sectional view of the burner plug,

Figure 3 is an elevation of one end of the 50 plug,

Figure 4 is an elevation of the opposite end of the plug,

Figure 5 is an enlarged transverse sectional view taken on the line shown in Figure 1 and looking in the direction of the arrows 5—5, and

Figure 6 is an enlarged transverse sectional view taken on the line shown in Figure 1 and looking in the direction of the arrows 6—6.

In the drawing the numeral 10 designates a cylindrical burner head which is formed with a dished face or forward end 11 and has an internally screw-threaded socket 12 at its inner or rear end. The socket terminates at an internal annular flange 13, and between this flange and the front wall of the head is an annular storage chamber 14.

The reduced screw-threaded pin 15 of an adapter 16 is screwed into the socket 12 against the flange 13. The adapter has an internal screw-threaded socket 17, which receives the end of a fuel supply tube 18. Oil, gas, or other fuel, or a mixture of fuels is fed through the tube 18 to the burner. It would be within the scope of the invention to screw the tube 18 directly into the head 10, and thus eliminate the adapter. It will be noted that the adapter has a bore 19 of substantially the same diameter as the tube, and when the head is removed this bore is exposed so that the tube may be readily cleaned or blown out.

A plug 20 is formed with a circumferential collar 21 at its intermediate portion, and this collar is provided with external screw-threads 22 adapted to engage in threads 23 provided in the flange 13. The plug has a flat face 24 at its forward end, and when said

plug is screwed into the flange, this face engages and forms a fluid-tight seal with the inner surface or flat face 25 of the front wall of the burner head 10.

5 The rear end of the plug is provided with a diametrical groove or recess 26 for receiving a screw driver or other tool, whereby said plug may be screwed into or removed from the head. On diametrically opposite sides 10 of the plug longitudinal ducts or grooves 27 extend forwardly from the ends of the groove 26. At their forward ends the ducts are provided with curved deflectors 28. It is pointed out that the ducts could be 15 milled and the milling tool would finish up the ducts with the curved deflectors 28. In this way the plug may be inexpensively produced. When the plug is screwed into the head, the deflectors extend into the annular 20 chamber 14 and consequently fuel received from the tube 19 and carried along the ducts is deflected or spread outwardly into the chamber 14.

The forward end of the plug is provided 25 with a circular chamber or recess 29, and a plurality of ducts 30 extend tangentially from this recess to the outer surface of the plug. By this arrangement fuel entering 30 the recess from the storage chamber 14 through the ducts 30 will be caused to whirl in said recess, and the turbulence thus set up will promote atomization and combustion. A substantially semi-spherical sump 31 is formed in the front wall of the head and 35 centrally located so as to register with the recess 29. It is preferable to make the base diameter of the sump the same as the diameter of the recess so that the joint between these parts will be flush and no obstruction 40 offered to a forward movement of the fuel fluid. A port 32 extends axially through the head from the sump, and is of a reduced diameter so as to eject the fuel fluid in a small stream or jet.

45 It is pointed out that the ducts 27 in the plug 20 provide free and unobstructed passages for the fuel fluid. The annular chamber 14 is of such size and capacity as to at all times store sufficient fuel fluid to prevent 50 starvation of the ports 30, recess 29 and sump 31. When the head is screwed off of the pin 15 the plug is carried with the head, and the bore 19 is immediately exposed. It is not necessary to unscrew additional parts to 55 secure such access. When the plug 20 is removed from the head the ducts 27, recess 29, and ports 30 are all exposed, and may be easily cleaned or inspected. This is particularly advantageous when compared with 60 those plugs in which the ports or ducts are bored or drilled through the plug.

Having illustrated and described a preferred form of the invention, what I claim, is:

65 1. In a fuel burner, a burner head having

a burner port at one end and a screw threaded internal flange intermediate its ends, a plug having a circumferential screw threaded collar intermediate its ends engaging in the flange of the head, the head having a storage chamber between its flange and its front wall surrounding the plug, the plug having a plurality of external fuel ducts extending substantially from end to end thereof and having at their forward ends deflectors curving gradually outward for directing the fluid fuel into the storage chamber of the head, the plug having also exterior ducts extending from the storage chamber and delivering fuel tangentially to the port of the head.

2. In a fuel burner, a burner head having a burner port in its front wall, a semi-spherical sump registering with the port and a screw threaded internal flange intermediate its ends, and a plug having a circumferential screw threaded collar intermediate its ends engaging in the flange of the head, the head having a storage chamber between its flange and its front wall surrounding the plug, the plug having a plurality of longitudinal exterior fuel ducts extending substantially from end to end of the plug and having curved deflectors at their forward ends for directing the fuel fluid outwardly into the storage chamber of the head, the plug having a flat forward end provided with exterior ducts extending from the storage chamber and delivering fuel tangentially to the semi-spherical sump.

3. In a fuel burner, a burner head having a burner port in its front wall, a semi-spherical sump registering with the port and a screw threaded internal flange intermediate its ends, and a plug having flat ends and a circumferential screw threaded collar intermediate its ends engaging in the flange of the head, the head having a storage chamber between its flange and its front wall surrounding the plug, the plug having a plurality of longitudinal exterior fuel ducts extending substantially from end to end thereof, provided with curved deflectors at their forward ends for directing the fuel outwardly into the storage chamber of the head, said plug having at its rear end a diametrical groove communicating at its ends with a pair of said longitudinal grooves, and having at its forward end a plurality of exterior grooves extending from the storage chamber in the head and delivering fuel tangentially to the semi-spherical sump.

In testimony whereof I affix my signature.

ROSS H. FORNEY.
